COMBINED TRUCK, DOLLY AND LADDER

Phil K. Tarran, 6709 Elmwood Road,
San Bernardino, Calif.

Filed Oct. 14, 1963, Ser. No. 76,953

Term of patent 14 years

(Cl. D14—3)

FIG. 1.

FIG. 2.

FIG. 1 is a perspective view of a combined truck, dolly and ladder taken from the front, one side and top thereof, embodying my design.

FIG. 2 is a perspective view thereof taken from the back, opposite side and bottom thereof.

I claim:

The ornamental design for a combined truck, dolly and ladder, as shown.
